Irmer et al. U.S. Appl. No. 10/047,847 filed Mar. 13, 2008.

* cited by examiner

Primary Examiner — Susan E Krakower(74) *Attorney, Agent, or Firm* — Merchant & Gould P.C.(57) **CLAIM**

The ornamental design for the roof module, as shown and described.

DESCRIPTION

FIG. 1 is a front view a roof module showing our design;

FIG. 2 is a top view thereof;

FIG. 3 is a first end view thereof;

FIG. 4 is a second end view thereof;

FIG. 5 is a rear view thereof;

FIG. 6 is a bottom view thereof; and,

FIG. 7 is a perspective view thereof.

The broken lines in FIG. 6 are included to illustrate unclaimed bottom portions of the roof module and form no part of the claimed design.
